United States Patent Office.

JOHN M. COOK, OF MARION, INDIANA.

Design No. 4,615, dated January 31, 1871.

DESIGN FOR A PLOW-CLEVIS.

The Schedule referred to in these Letters Patent and making part of the same.

To all whom it may concern:

Be it known that I, JOHN M. COOK, of Marion, in the county of Grant and State of Indiana, have invented a new and original Design for a Plow-Clevis; and I do hereby declare that the following is a full, clear, and exact description thereof, which will enable others skilled in the art to make and use the same, reference being had to the accompanying drawing forming part of this specification.

The drawing represents a perspective view of my new design for a plow-clevis.

This invention relates to a new form of swivel plow-clevis.

The same is composed of three parts, A B C.

The part A is a plate affixed to the top of the plow-beam and provided with a downwardly-extending plate *a* at its front end.

The part C is a rod, fitted through a heart-shaped slot of the plate *a* and secured with its rear end to a bolt, B, which is suspended from the rear end of the plate A, being held thereto by a nut, *b*.

It will be noticed that the plate *a* is considerably broader than the plate A, to which it is secured, so as to allow full lateral play to the draft-rod C.

The latter has an eye, *c*, at its front end to receive the whiffletree or other draft apparatus.

I claim as my invention—

The design for a plow-clevis, herein described.

The above specification of my invention signed by me this   day of   1870.

JOHN M. COOK.
